UNITED STATES PATENT OFFICE

BORNETT L. BOBROFF, OF RACINE, WISCONSIN

DESIGN FOR A VEHICLE TAIL LAMP

Application filed August 11, 1930. Serial No. 36,622. Term of patent 14 years.

To all whom it may concern:

Be it known that BORNETT L. BOBROFF, a citizen of the United States, residing at Racine, in the county of Racine and State of Wisconsin, has invented a new, original, and ornamental Design for Vehicle Tail Lamps, of which the following is a specification, reference being had to the accompanying drawing, forming part thereof.

I claim:

The ornamental design for a vehicle tail lamp, as shown.

BORNETT L. BOBROFF.
